Patented Feb. 13, 1962

192,238

CARRYING CASE FOR A PHOTOGRAPHIC CAMERA OR SIMILAR ARTICLE

Allen R. Obergfell, Niles, Ill., assignor to Bell & Howell
Company, Chicago, Ill., a corporation of Illinois

Filed Oct. 23, 1961, Ser. No. 67,222

Term of patent 14 years

(Cl. D87—5)

FIG. 1.

FIG. 2.

FIGURE 1 is a perspective view of a carrying case for a photographic camera or similar article; and

I claim:

The ornamental design for a carrying case for a photographic camera or similar article, as shown.
